ROPE FORMING MACHINE

Sherwood C. Hall, Redwood City, Calif.

Application October 17, 1950, Serial No. 190,557

6 Claims. (Cl. 57—31)

1

This invention relates to rope or twine-manufacturing machines, and more particularly to a machine which produces rope, twine or cord by elongating and stretching a ribbon, filament or strand material, and then forms strands by helically winding various numbers of elongated ribbons, filaments or strands.

A main object of the invention is to provide a novel and improved rope, twine or cord-forming machine wherein a ribbon, filament or strand material is elongated or stretched, increasing its length by reduction of width and thickness, said reduction being regulated in a definite manner so that the material can be stretched a desired amount and uniformly twisted and stranded, whereby the resultant product is characterized by constancy in strength, size and appearance along its length.

A further object of the invention is to provide an improved rope, twine or cord-forming machine which is simple in construction, which is reliable in operation, and which provides a stronger, harder, better-formed and more uniform strand than is obtainable with machines of the prior art.

Further objects and advantages of the invention will become apparent from the following description and claims, and from the accompanying drawings, wherein:

Figure 1 is an elevational view, partly in cross-section, of the strand-forming portion of a machine constructed in accordance with the present invention;

Figure 2 is an enlarged plan view of one of the reduction frames employed in the strand-forming machine of Figure 1;

Figure 3 is an enlarged cross-sectional detail view taken on line 3—3 of Figure 1;

Figure 4 is a cross-sectional detail view taken on line 4—4 of Figure 3;

Figure 5 is an enlarged cross-sectional detail view taken on line 5—5 of Figure 2.

Referring to the drawings, the figures disclose and illustrate a strand-forming assembly which is suitable for mounting on a suitable base in the same general manner as disclosed in my prior Patent No. 2,495,251, issued on January 24, 1950. Designated at 11 is a shaft which is driven by a suitable electric motor, not shown, and which carries a large bevel gear, shown at 12, rigidly secured thereto. Secured to the shaft 11 adjacent the bevel gear 12 is a large transversely extending support plate 28 which may be circular in shape. Secured to the shaft 11 at its end opposite the bevel gear 12 is another support plate 34 which is parallel to the plate 28 and which may also be circular in shape. Designated at 13, 13 are respective elongated frames which are journaled to the support plates 28 and 34 on respective axes which converge toward the smaller support plate 34. The left ends of the frames 13, as viewed in Figure 1, are journaled in respective bearings 14, 14 carried by the support plate 28, and the shafts of said frames 13, 13 extend through the bearings 14 and have secured thereto on the respective bevel gears 33, 33. Designated

2

at 15, 15 are respective shafts journaled in bearing brackets 16 secured to the support plate 28, the shafts 15 carrying at their ends respective bevel gears 17 and 31. The gears 17 mesh with the large bevel gear 12 and the gears 31 mesh with the bevel gear 33, as shown in Figure 1. Therefore, as the shaft 11 is rotated, rotary motion is transmitted to the frames 13, 13 through the bevel gears 12, 17, 31 and 33, whereby the frames 13 rotate around their respective axes simultaneously with the rotation of the shaft 11.

Each frame 13 comprises respective end plates 18 and 19 connected by a plurality of longitudinal bolts 20 defining a rectangular framework. As shown in Figure 1, the plate member 18 has axially secured thereto the shaft portion 32 which defines a spacing shoulder disposed adjacent the bearing 14, the remainder of the shaft of the frame 13 being reduced in size and extending through the bearing sleeve 14. The gear 33 is secured to the end of said reduced shaft and cooperates with the shouldered shaft portion 32 to restrict longitudinal movement of the frame relative to the bearing 14. At the opposite end of the frame, the support member 34 is formed with a bearing sleeve 21 which has a reduced bearing portion 22. Secured to the plate 19 is an annular bearing sleeve 23 which is rotatably received on the stationary sleeve 22, a suitable bearing bushing 24 being interposed between the sleeve 23 and the stationary sleeve 22. Secured to the internal walls of the stationary bearing 21 are the parallel, longitudinally extending, spaced arms 25, 25, between which are journaled the longitudinally spaced rollers 9', 10', 11', as shown in Figures 1 and 5. Secured to the bolts 20 on respective opposite sides of each frame 13 are transversely aligned bracket bars 26, 26 on the intermediate portions of which is journaled a shaft 27 carrying a reel 28'. Secured to the bolts 20 on the respective opposite sides of each frame 13 are the respective pairs of brackets 29', 29', 30', 30' and 31', 31', longitudinally spaced along the frame in the manner illustrated in Figure 2. The brackets 29', 29' are formed with inwardly facing, T-shaped grooves 32', 32'. Designated respectively at 1, 2, 3 and 4 are rollers which are supported on the opposed bracket members 29', 29'. As shown in Figures 3 and 4, the grooves 32' have fixed stop elements in their lower ends, shown at 33', and the shaft of the roller 1, shown at 34', is mounted on bearings 35', 35' which are received in the grooves 32', 32' and urged against the stop members 33' by spacer blocks 36'. Similarly, the roller 2 is provided with a shaft 37' which is mounted on bearings 38' received in the grooves 32' and bears against the spacer 36' by additional spacers 39'. The shaft of the roller 3, shown at 40', is mounted on bearings 41' which are urged against the spacers 39' by additional spacers 42'. The shaft of the roller 4, shown at 43', is mounted on bearings 44' received in the groove 32', and engaged by respective parallel lugs 45', 45' rigidly secured to a bar member 46' secured to the top ends of the brackets 29', 29', as viewed in Figure 3, by respective headed screws 47', 47', which

are threaded into the brackets 28', 29'. Respective coil springs 48' are provided on the screws 47' bearing between their heads and the bar member 46', and biasing the lug members 45' into engagement with the bearings 44'. The springs 48', therefore, exert a biasing action on the respective roller shafts, urging the roller shafts toward normal positions and urging the rollers 1 and 3 toward the roller 2. The rollers 1 and 3 are of hard material, and the rollers 2 and 4 are relatively yieldable material, such as soft rubber or the like. The roller 3 is non-circular in cross-section, and, as shown in Figure 1, has four arcuate grooves in its surface evenly spaced around the axis of the roller, said grooves being shown at 49'. The rollers 2 and 4 are relatively large as compared with the rollers 1 and 3.

Journaled to the intermediate portions of the brackets 30', 30' is a relatively large roller 6 of soft material, such as rubber or the like. Journaled between the bracket bars 31', 31' are the respective rollers 5, 8 and 7, of relatively hard material, said rollers being relatively small as compared with the roller 6. Designated at 47 is an annular forming die which is suitably mounted in a stationary position on a portion of the main frame of the machine, in a manner similar to that disclosed in my above-mentioned prior Patent No. 2,495,251, the forming die 47 being axially aligned with the shaft 11 and spaced outwardly with respect to the support member 34. The forming die 47 may be generally conical in shape, as shown in Figure 1.

The reels 28', 28' have wound thereon the material from which the rope is to be formed, for example, plastic web material such as polythene transparent plastic web material approximately two inches wide. The web material is threaded around the rollers 2, 4, 5, 6, 7, 8, 9', 10' and 11', in the manner shown in Figure 1, and extends through the forming die 47, and is anchored to a winding drum, not shown, in the same manner as described in my above-mentioned prior Patent No. 2,495,251. As shown in Figure 1, the roller 5 is preferably non-circular in cross-section, for example, square in cross-section.

In operation, the material starts its controlled elongation by passing between rollers 1 and 2, and then around roller 2 and between rollers 2 and 3, and thence up and over roller 4 and around roller 5. The material then goes back and around roller 6 and under and around roller 7, then between rollers 7 and 8 and around roller 8 and between rollers 9', 10' and 11', as shown, thence between the arms 25, 25 through the stationary bearing 21 and through the annular die 47. Control of the elongation of the material as it passes the rollers 1, 2 and 3 is provided by regulating the tension of the springs 48' by means of the screws 47'. During operation of the machine, the relatively hard roller 1 embeds itself against the soft roller 2 to a degree controlled by the tension of the springs 48', the plastic material being initially elongated and reduced in width as it passes between the rollers 1 and 2, as shown in dotted view in Figure 2. Because of the cross-sectional shape of the roller 3, the material is intermittently gripped and held by the embedding of the ridges on the roller 3, as said roller rotates against the roller 2. This provides a controlled hesitation of the travel of the material through the rollers 2 and 3, creating a building up of tension in the material which has emerged from between the rollers 2 and 3. This tension trips the roller 3 periodi-

cally, causing an increase in the speed of movement of the material each time that the roller 3 moves into a position wherein one of its concave surfaces bears against the roller 2. There results an alternate gripping and releasing action provided between the rollers 2 and 3, whereby the tension is built up and elongation takes place on the material, the degree of this action being controlled by regulating the tension of the springs 48' by means of screws 47'. The material leaving roller 3 passes over roller 4 and thence over square roller 5. Roller 5, in view of its square shape, aids in the tripping action at roller 3 by providing a pulsation in the tension developed in the material. After the material passes over and around roller 5, it passes over roller 6 which is a soft roller and which absorbs some of the shock provided by the square roller 5. The material then passes around roller 7 and over roller 8, and thence alternately below and above rollers 9', 10', and 11', in the manner shown in Figure 1. As the material leaves roller 11', it is twisted in view of the rotation of the frames 13, the twisted strands emerging from the respective bearings 21 being again twisted in the forming die 47 because of the rotation of the shaft 11, which rotates the frames 13 bodily as they rotate individually around their respective axes. The respective component strands leaving the twisting frames 13 are shown respectively at 50', 50'. Any desired number of component strands 50' may be provided by providing the corresponding number of twisting frames 13 between the supporting members 28 and 34.

While a specific embodiment of an improved rope-forming machine has been disclosed in the foregoing description, it will be understood that various modifications within the spirit of the invention may occur to those skilled in the art. Therefore, it is intended that no limitations be placed on the invention except as defined by the scope of the appended claims.

What is claimed is:

1. A rope-forming machine comprising a shaft, a first transverse support member secured on said shaft, a second transverse support member secured on said shaft and spaced longitudinally from said first support member, a plurality of frames journaled on said support member, the axes of the frames converging toward the second support member, means coupling said shaft and said frames for simultaneous rotation around their respective axes, a reel journaled transversely on each frame, a plurality of transverse forming rollers journaled on each frame between the reel and the end of the frame adjacent the second support member, spring means on each frame biasing certain of the forming rollers on each frame relative to other of the rollers thereon, at least one of said certain rollers being polygonal in cross-section, said second support member being provided with respective hollow bearings rotatably supporting the frame, a pair of parallel arms rigidly secured on each hollow bearing and extending inwardly of the frame associated therewith parallel to the axis thereof, a plurality of spaced additional rollers journaled transversely between each pair of parallel arms and aligned with the axis of the associated frame, and an annular stationary die axially aligned with said shaft outwardly adjacent said second support member.
2. In a rope forming machine, a frame mounted

for rotation about its longitudinal axis, a reel journaled transversely on said frame, a first set of forming rollers journaled transversely on the frame, spring means associated with said first set of rollers for biasing the rollers relative to each other, a second set of forming rollers transversely journaled on the frame and longitudinally spaced from the first set of rollers, one of said rollers of the second set being non-circular in cross section, a guide roller journaled transversely on the frame and interposed longitudinally between the first and second set of forming rollers, the guide roller receiving the material from the non-circular roller of the second set and advancing the material to the other rollers of the second set, and a plurality of spaced additional rollers journaled transversely on the frame and lying along with the axis of the frame.

3. A rope forming machine comprising a shaft, a first transverse support member secured on said shaft, a second transverse support member secured on said shaft and spaced longitudinally from said first support member, a plurality of frames journaled on said support members, the axes of the frames converging toward the second support member, means coupling said shaft and said frames for simultaneous rotation around their respective axes, a reel journaled transversely on each frame, a first set of transversely arranged forming rollers journaled for rotation on each frame between the reel and the end of the frame adjacent the second support member, spring means associated with the first set of forming rollers on each frame biasing certain of the forming rollers relative to each other, at least one of said rollers of the first set being non-circular in cross section, a second set of forming rollers transversely arranged on each frame, adjacent to the end of the frame adjacent the second support member, said rollers of the second set being journaled for rotation on the frames, said second support member being provided with respective hollow bearings rotatably supporting the frames and adapted to receive the rope forming material from the second set of rollers, and an annular stationary die axially aligned with said shaft outwardly adjacent said second support member and receiving the rope forming material from each of the frames.

4. In a rope forming machine, a frame having a first end and a second end, said frame being journaled at its ends for rotary movement, a reel transversely journaled in the frame adjacent the first end, a first set of forming rollers transversely journaled in the frame adjacent the reel and disposed in a plane transverse to the frame, spring means associated with the rollers of the first set for biasing certain of the rollers into peripheral engagement, a second set of forming rollers journaled for rotation in the frame adjacent the second end thereof and disposed in another plane transversely of the frame, one of said rollers of the second set receiving the rope forming material from the first set of rollers, a roller journaled transversely in the frame intermediate the first and second sets of rollers and adapted to receive the material from the said roller of the second set and advance the material to the other rollers of the second set, a plurality of spaced additional rollers journaled transversely in the frame adjacent the second end and lying along the axis of the associated frame, said additional rollers being in a position between the second set of rollers and the second end and aligned with the axis of the associated

frame for receiving the material from the other rollers of the second set, the second end of said frame being formed with a hollow bearing rotatably supporting the frame and receiving the material from the additional rollers.

5. In a rope forming machine, a frame having a first end and a second end, said frame being journaled at its ends for rotary movement, a reel transversely journaled in the frame adjacent the first end, a first set of forming rollers journaled in the frame adjacent the reel and disposed in a plane transversely to the frame, spring means associated with the rollers of the first set for biasing certain of the rollers into peripheral engagement, a second set of forming rollers journaled in the frame adjacent the second end thereof and disposed in another plane transversely of the frame, one of said rollers being non-circular in cross section and receiving the rope forming material from the first set of rollers, a roller journaled transversely in the frame intermediate the first and second sets of rollers and adapted to receive the material from the said roller of the second set and advance the material to the other rollers of the second set, said second end of the frame being formed with a hollow bearing rotatably supporting the frame and adapted to receive the material from the said rollers of the second set.

6. In a rope forming machine, a frame having a first end and a second end, said frame being journaled at its ends for rotary movement, a reel transversely journaled in the frame adjacent the first end, a first set of forming rollers journaled in the frame adjacent the reel and disposed in a plane transversely to the frame, spring means associated with the rollers of the first set for biasing certain of the rollers into peripheral engagement, a second set of forming rollers journaled in the frame adjacent the second end thereof and disposed in another plane transversely of the frame, one of said rollers being non-circular in cross section and receiving the rope forming material from the first set of rollers, a roller journaled transversely in the frame intermediate the first and second sets of rollers and adapted to receive the material from the said roller of the second set and advance the material to the other rollers of the second set, said second end of the frame being formed with a hollow bearing rotatably supporting the frame and adapted to receive the material from the said rollers of the second set, and a plurality of spaced additional rollers journaled transversely in the frame adjacent the second end and lying along the axis of the frame, the rollers being operatively interposed between the said rollers of the second set and the second end of the frame.
